UNITED STATES PATENT OFFICE.

JAMES H. MINER, OF LUMBERTON, MISSISSIPPI.

ACETYLENE-GAS GENERATOR.

1,050,158.

Specification of Letters Patent. Patented Jan. 14, 1913.

Application filed December 13, 1911. Serial No. 865,549.

To all whom it may concern:

Be it known that I, JAMES H. MINER, citizen of the United States, residing at Lumberton, Mississippi, have invented certain new and useful Improvements in Acetylene-Gas Generators, of which the following is a specification.

My present invention relates to improvements in acetylene gas generators of the carbid feed type.

All of the valves governing the feed of carbid to the water of which I am aware, while they serve to properly cut off the carbid, do not close air-tight, the result of which is that the carbid within the carbid holder is more or less subject to the action of the moisture within the water chamber, and where the gas is not drawn upon for any material length of time, the carbid is not kept fresh, and considerable loss ensues.

The present invention has for its object to prevent this access of moisture to the carbid, to prevent any excess of feed or over feeding, to insure the positive closing of the main valve when necessary to prevent over feeding.

With these and other objects in view, the invention includes the novel construction hereinafter described and particularly pointed out in the appended claims.

An embodiment of the invention is illustrated in the accompanying drawing, in which—

Figure 1 shows an acetylene gas generator in sectional elevation with the bell elevated, and Fig. 2 a partial view thereof with the bell lowered. Fig. 3 is an enlarged sectional view of the valve.

Referring by reference characters to this drawing, the numeral 1 designates the water chamber or tank within which is guided the gasometer bell 2. Within the bell is located a stationary carbid receptacle 3 which is supported upon springs 3^a which, in turn, rest upon standards 3^b supported from the bottom of the tank. This carbid receptacle is preferably of inverted conical shape and terminates in a delivery opening 3^c. The delivery opening 3^c is normally closed by an inwardly opening valve 4 provided with an upwardly extending stem 4^a guided by a spider 4^b. As the bottom wall of the hopper is of inverted conical shape I find that a very simple and efficient form of valve is that in which a weight or heavy body is

used having its lower face also of inverted cone shape to coact with the flaring wall of the carbid receptacle adjacent the delivery opening. The valve is lifted by a depending rod or stem 4^c which has its lower end in line with a contact portion 5^a of a lever 5 fulcrumed on an arm 6 depending from the carbid receptacle. To the outer or free end of the lever 5 is connected the lower end of a weighted rod 7 connected at 65 its upper end to one end of a lever 8 fulcrumed upon an arm 9 extending upward from the upper side of the carbid chamber, which upper side is also of substantially cone shape. The weighted rod normally 70 keeps lever 5 depressed so that the valve is allowed to close by gravity so that no carbid drops into the water.

When pressure of gas beneath the bell lowers due to the gas being drawn off 75 through the outlet pipe and the necessity for more carbid, the bell lowers until it contacts with the end 8^a of the lever 8. This pulls upwardly on the rod 7, and rocks lever 5, causing it to push upward on stem or rod 4^c raising the valve and permitting carbid to drop through into the water until the pressure of the generated gas is sufficient to raise the bell, when lowering of lever 5 permits the valve to quickly close by gravity 85 and cut off a further feed of carbid.

It is rendered imperative, by reason of the regulations of the fire underwriters, that any valve used must be an inwardly opening valve. But any inwardly opening valve, 90 when it closes, while it will effectually cut off further feed, yet will not close gas tight because gas will necessarily work its way through between the particles of carbid which are clamped, in the closing of the valve, between the valve and its seat. This is a serious objection if the generator stands for any material length of time without the carbid being drawn upon as the slow and gradual access of moisture laden gas tends to deteriorate the carbid. To avoid this objection and effect a gas tight joint or seal, 95 I provide the vertical rod 4^c with a disk c of rubber or like flexible elastic material which, when the valve is closed, presses at its edge against a depending flange surrounding the delivery opening of the carbid receptacle and effects a gas tight seal. The valve is provided with a funnel shaped opening 4^d and the upper end of the rod 4^c ex- 100 105 110

tends into this and is capable of limited vertical movement before lifting the weighted valve.

When the lever 5 raises the rod 4^c the rod 5 first moves upward without raising the valve, causing the flexible disk to be shoved upward into the funnel shaped opening which effects the closing of the flexible member in a manner similar to the closing of an 10 umbrella. Further upward movement lifts the valve while retaining the flexible member in its folded position. The vertical rod 4^c is guided into a cylindrical recess "e" formed in the lower portion of the valve 4 and continuous with the funnel shaped opening 4^d.

The reservoir is filled with fresh carbid when the bell is in its lowermost position by means of a removable cap 9^a which covers 20 an opening 10 in the top of the bell, which latter opening is closed by a removable plug 12. This plug serves to effectually seal the carbid hopper against access of moisture from the gas compartment through the feed 25 opening.

In order to indicate the amount of carbid within the carbid hopper, I provide depending from the latter a rod 13 which extends downward to a point below the edge of the 30 bell, and thence upward, where it is connected to the short arm 14 of the two-armed lever pivotally mounted on the edge of the water tank, the other end of which constitutes an indicating arm 15. When the carbid chamber is full, the springs will allow 35 the carbid chamber to settle, and the long arm or indicator will lie in a vertical position, but as the carbid chamber is emptied, the indicating arm will be swung over

toward a horizontal position, thus indicating, by its position, the amount of carbid in the hopper.

Having thus described my invention what I claim is:

1. In an acetylene gas generator a carbid hopper having a delivery opening and a depending flange around said opening, an inwardly opening gravity closing valve for controlling the carbid feed, a vertical rod in operative engagement with said valve, means for moving the rod upward to open the valve, a disk of flexible resilient material carried by said rod and co-operating with said depending flange, when the valve is closed, to effect a gas tight joint, and means for effecting the folding of said disk as the valve is opened.

2. In an acetylene gas generator, a carbid hopper having a delivery opening and a depending flange around said opening, an inwardly opening valve co-operating with said opening for controlling the carbid feed, said valve having a funnel-shaped opening in its lower side, a vertical rod movably sustained within said flange and having its upper end in line with said funnel-shaped opening, means for elevating said rod to unseat the valve, and a disk of flexible resilient material carried by said rod and arranged to be carried by the upward movement of said rod into said funnel-shaped opening to effect folding of the disk.

In testimony whereof, I affix my signature in presence of two witnesses.

JAMES H. MINER.
